ROTATABLE DISPLAY EQUIPMENT

Hal L. Jones and Charles Ray Jones, Joplin, Mo.

Application July 11, 1931. Serial No. 550,184

18 Claims. (Cl. 211—74)

This invention relates to devices for displaying goods in retail stores and particularly to means for displaying canned goods.

In retail stores, it is common practice to arrange canned goods on shelves, but inasmuch as the goods are in cans, the customer is obliged to take the goods on credit as it were, being unable to see any samples of the goods contained in the cans.

10 The present invention is designed to provide means whereby a transparent jar containing the same goods as are contained within the cans may be disposed in juxtaposition to the cans of goods so that the customer may see just exactly what is being bought.

15 A further object in this connection is to provide means whereby the transparent jar containing the sample of the goods may be readily rotated so that the customer can secure a good view of the contents.

20 A still further object is to provide a display device which is attachable to a shelf and which will hold the transparent jar in immediate conjunction with the canned goods of which the jar 25 is a specimen, and a further object in this connection is to make it possible for accurately setting up this display attachment and the cans themselves so that the transparent jar will be in proper position with relation to the adjacent cans.

25 A further object is to provide a support for the transparent jar so constructed that the jar may be rotated by the salesman or by the customer without in any way disturbing the adjacent cans.

30 Other objects will appear in the course of the following description.

Our invention is illustrated in the accompanying drawings, wherein:—

Figure 1 is a top plan view of our attachment 40 and three adjacent cans arranged upon a shelf;

Figure 2 is an elevation of two tiers of cans and the transparent specimen jar;

Figure 3 is a side elevation partly in section of the cans and jar as shown in Figure 2;

Figure 4 is an under side plan view of the upper jar supporting plate.

Referring to these drawings, A designates a shelf upon which the goods are to be displayed and B an upper shelf, C designating a plurality of cans filled with canned goods such as peaches, tomatoes or the like. Our attachment comprises a base plate 11 having an upwardly extending rim or flange 12 supporting a dummy can 13. 50 This dummy can may have advertising matter

thereon or may have the same ornamentation and descriptive matter as is placed upon the can C.

The base plate 11 is circular in form and is laterally extended as at 14, this extension 14 being in the form of an approximate square, the square having concavely curved side edges 14a so as to fit within a space defined by three cans as illustrated in Figure 1, these three cans being arranged in symmetrical relation so as to present an attractive, orderly appearance on the shelves. The 60 dummy can 13 is preferably attached to the supporting plate 11 and also extending upward from this supporting plate is a tubular stem or standard 15.

Adapted to be disposed on the upper end of the dummy can 13 is a plate 16 having the same shape as the plate 11 but having a downwardly extending annular flange 17 which fits closely within the dummy can 13. The dummy can 13 is vertically slotted at 18 and carried upon the downwardly projecting lugs 19 formed on the under side of the plate 16 is an operating shaft 20 whose outer end extends out through the slot 18 and carries a knurled head 21. The inner end of this shaft carries the beveled gear wheel 22. Extending upward through the center of the plate 16 is a vertical shaft 23 carrying at its lower end the beveled gear wheel 24. The upper end of this shaft carries upon it the disk 25 having an upwardly extending annular flange 26 and upwardly extending fingers 27, these fingers being adapted to embrace and receive the lower end of a transparent jar 28 containing a sample of the goods as disposed in the can C. This jar is, of course, to be sealed and to be in all respects a fair sample of the goods as contained within the cans C. The plate 25 with the flange 26 and fingers 27 constitutes a holder for the jar. 70 75 80 85 90

It will be seen that with this construction, when the knurled head 21 is turned, the jar holder and the jar will be rotated so that the contents of the jar can be seen by the customer. A washer 29 is disposed between the bottom of the holder 25 and the upper face of the plate 16 so as to permit a free rotation of the holder and a washer or equivalent member 30 surrounding the shaft 23 below the plate 16 so as to hold the gear wheel 24 in engagement with the gear wheel 22. 95 100

The plate 16 is also outwardly extended at 31, this outward extension being approximately 105 square with reentrant or concavely curved edges of exactly the same type as the extension 14 so as to fit in the space between three symmetrically disposed cans as shown in Figure 1. The tubular stem or standard 15 extends upward through the 110

extension 31 and engaged in this standard is the screw 32, the upper end of which is tapered to a four-sided point at 33. Engaging the screw-threads of this screw 32 is a nut 34 which bears against the upper end of the tubular stem 15. It will thus be obvious that as the nut is rotated in one direction, the screw 32 will be forced upward and its point will be forced into the upper shelf B as shown clearly in Figure 3, thus locking the attachment in place against accidental dislodgement. Preferably the upper end of the screw just below the point 33 is knurled at 35 to permit the holding of the screw by the fingers while the equipment is being screwed in position by the tightening of the adjusting nut 34. Thus adjustment of the rod and nut permits the equipment to be quickly and securely set up or as quickly removed, without the use of any tools, tacks, nails or screws. Furthermore, this permits the equipment to be adjusted to various heights between shelves.

It is to be noted that the dummy can 13 and the plates 16 are both provided with protruding rims which immediately contact with the cans C and cause a space to be formed between the body of the jar 28 and the surfaces of the cans C to thus permit free rotation of the jar.

While we have heretofore referred to the use of this transparent jar 28 and the means for supporting and rotating it in connection with canned goods or tinned goods, obviously we do not wish to be limited to this as the device might be used in connection with goods put up in glass, the device under these circumstances permitting the customer to rotate the transparent jar supported by the display equipment so that the customer can secure a thoroughly good inspection of the sample jar without having to take down any of the jars arranged upon the shelf for this inspection.

Preferably, as before stated, the dummy can 13 which constitutes a support for the transparent jar will be labeled and will have the appearance of the remainder of the cans, though obviously we do not wish to be limited to this.

It will be noted that we have made use of the space between the cans of goods created by the common practice of stacking cans in front of each other, to the side of each other and on top of each other on the shelves. The extensions 14 and 31 cross this otherwise useless space so that the shelf engaging means is practically entirely concealed within this space and the cans on the shelves, together with the supporting base 13 or dummy can and transparent jar 28 may seem as a harmonious whole.

While we have illustrated the jar 28 as being rotatable by means of the knurled head 21, we do not wish to be limited to this as the jar might be rotated intermittently by a spring motor, electric motor or other power. By our device, we are enabled to adjust the equipment to different spaced shelves and securely hold the display device in place so that it cannot be accidentally knocked off the shelf in removing adjacent cans.

As illustrated in the drawings, our display device permits the cans or other containers to be disposed in parallel rows upon the shelves, the rows being parallel to the front edge of the shelf and it is to be noted in this connection that the knurled head whereby the sample can is turned is disposed at an angle to the edge of the shelf so that it does not protrude beyond the shelf and is thus not likely to catch on garments when removing cans from the shelf or anything of this

nature. The upper lateral projection 31 keeps the cans properly spaced from each other but it is to be understood that this lateral projection does not touch the sides of the cans C but engages the upper rim of the lower can and the lower rim of the upper can. Thus this extension acts as a guard against possible dislodgement of the cans on the top row and also acts as a guard to cans on the lower row.

While we have before referred to the use of this equipment in connection with cans, it is to be understood that by the term "cans" we include any form of jar or container to which our equipment is adapted, whether these jars are transparent or whether they are closed cans. This equipment while particularly adapted to be used on shelves of retail stores, could be used very effectively on the shelves of sales rooms of wholesale houses to show to the prospective buyer the contents of the canned goods which he is interested in purchasing. This does away with the cutting open of canned goods for inspection and this does away with waste.

While we believe the details of construction to be particularly effective, we do not wish to be limited to these details, except as defined in the appended claims.

We claim:—

1. A display device of the character described, including a cylindrical support, means for clamping the support to a shelf, a cap insertible into the upper end of the support, a jar holder rotatably mounted upon the cap and having means for engaging the lower end of a transparent jar, and means whereby the jar holder may be rotated upon the support. 105

2. A display device of the character described, including a cylindrical support, the lower end of the support having an outwardly extending flange, a cap insertible into the upper end of the support and having an outwardly extending flange, said flanges acting to space adjacent cans from the support, and a jar holder rotatably mounted upon said cap. 115

3. A display device of the character described, including a cylindrical support, the base of said support having a lateral extension, a cap engageable with the upper end of the support, and having a lateral extension, the lateral extensions of the support and cap having three concave side edges adapted to fit the curvature of three stacks of adjacent cans placed in juxtaposition to the support, means carried by the extension of the base for clamping the support in place on a shelf, and a jar holder rotatably mounted upon the cap. 125 130

4. A display device of the character described, including a cylindrical support, the base of said support having a lateral extension, a cap engageable with the upper end of the support, and having a lateral extension, the lateral extensions of the support and cap having three concave side edges adapted to fit the curvature of three stacks of adjacent cans placed in juxtaposition to the support, a tubular stem extending upward from the extension of the base and through the extension of the cap, a screw-threaded clamping element having its lower end disposed within said tubular extension, the upper end of the element being pointed and a nut engaging the screw-threaded element and bearing against the upper end of the tubular stem. 135 140 145

5. A jar display device including a support, a jar holder mounted on the support, the support having a lateral extension, a tubular stem extending upward from the extension, a shelf en- 150

- gaging screw disposed within said stem and having its upper end pointed, and a nut bearing against the upper end of the stem and engaging the screw.
- 5 6. A display device of the character described, including a hollow cylindrical support having a lateral extension, a cap having a downwardly extending flange fitting within the upper end of the support and having a lateral extension, the lateral extensions being formed to engage with the rims of adjacent cans and space said cans symmetrically, means for clamping the support to a shelf, and a rotatable jar holder mounted upon and carried by said cap. 80
- 10 7. A display device of the character described, including a hollow cylindrical support having a lateral extension, a cap having a downwardly extending flange fitting within the upper end of the support and having a lateral extension, the lateral extensions being formed to engage with the rims of adjacent cans and space said cans symmetrically, means for clamping the support to a shelf, a rotatable jar holder mounted upon and carried by said cap, a shaft extending downward from the holder through the cap and carrying a beveled gear wheel, a shaft extending laterally through the flange of the cap and having a beveled gear engaging the first-named beveled gear wheel, the side wall of the support being vertically slotted downward to accommodate said shaft. 90
- 15 8. A display device of the character described, including a hollow cylindrical support having a radial extension, a cap having a downwardly extending flange contained within the upper end of the support and having a radial extension in alinement with the lower radial extension, the radial extensions being formed to engage with adjacent cans and space said cans uniformly on the shelf, means passing through said extensions for clamping the support to the shelf, a rotatable jar holder mounted upon and carried by said cap, and means for rotating said jar holder including a manually operable member having its axis disposed radially and in line with the radial extensions but on the opposite side of the jar holder from said radial extensions. 95
- 20 9. A merchandising and display equipment comprising the combination of a shelf adapted to support a supply of sealed opaque containers of goods, a transparent jar adapted to contain specimens of the goods stored in said containers, a support for the transparent jar having approximately the same diameter as and the similitude of one of the sealed opaque containers, and a rotatable jar holder mounted upon the upper end of said support. 100
- 25 10. A merchandising and display equipment comprising the combination of a shelf adapted to support a supply of sealed opaque containers of goods, a transparent jar adapted to contain specimens of the goods stored in said containers, a support for the transparent jar having approximately the same diameter as and the similitude of one of the sealed opaque containers, a rotatable jar holder mounted upon the upper end of said support, and means on the support disposed inward of the edge of the shelf whereby the support may be clamped to a shelf. 105
- 30 11. A merchandising and display equipment comprising the combination of upper and lower shelves adapted to store a supply of sealed cans containing food products and disposed between the shelves, a transparent jar adapted to contain a specimen of the goods contained in said sealed cans, a support for said jar adapted to rest upon the lower shelf and having approximately the same diameter as and the similitude of the sealed cans, a rotatable jar engaging member mounted upon said support and supporting the jar for rotation, and means for clamping the support between said shelves. 110
- 35 12. A merchandising and display equipment comprising the combination of a shelf adapted to support a supply of sealed opaque containers of goods, a transparent jar having a height approximating the height of a sealed container, and a diameter approximating the diameter of a sealed container and adapted to contain a specimen of the goods stored in said containers, and a cylindrical support for the jar having a height approximately the same as the height of the sealed containers and a diameter approximately the same as that of the sealed containers and having the similitude of said containers, a rotatable member mounted upon said support and supporting and engaging the jar, and manually operable means projecting through the side wall of the support whereby the jar may be rotated. 115
- 40 13. A merchandizing and display equipment comprising in combination a shelf adapted to support two tiers or sealed opaque cylindrical containers, a transparent jar having a diameter approximately the same as the diameter of one of the sealed containers and adapted to contain specimens of the goods in said containers, a support for the transparent jar having approximately the same diameter and height as one of the sealed containers and adapted to be disposed in the lower tier with said containers, and a rotatable jar holder mounted upon the upper end of said support. 120
- 45 14. As an article of manufacture, a cap having a flange adapted to be inserted within the upper end of a dummy can, the cap being laterally extended beyond said flange, a jar holder rotatably mounted upon the upper face of the cap, a base plate having means for supporting the bottom of the said dummy can and extending laterally beyond said means, a tubular stem extending upward from the base plate and extending through the lateral extension of the cap, and a screw having telescopic engagement with the stem and extending up therefrom and adapted to engage against an upper shelf, and a nut engaging the threads of the screw and bearing against the upper end of the stem. 125
- 50 15. A merchandising and display equipment comprising upper and lower shelves adapted to support sealed opaque cylindrical containers, a transparent jar having a diameter approximately the same as the diameter of one of the sealed containers and adapted to contain specimens of the goods in one of the containers, a support for the transparent jar having the similitude of one of the sealed opaque containers and adapted to be disposed on the lower shelf with the said containers, a rotatable jar holder mounted upon the upper end of said support, and means engaging the support and engaging the upper and lower shelves to hold the support with the transparent jar thereon against movement from between the shelves. 130
- 55 16. A merchandising and display equipment including in combination two shelves adapted to support between them sealed opaque cylindrical containers, a transparent jar adapted to contain specimens of the goods in said containers, a support for the transparent jar and adapted to rest upon a lower shelf, and having the similitude of the cylindrical containers, and means carried by 135
- 60 17. A merchandising and display equipment comprising the combination of upper and lower shelves adapted to store a supply of sealed cans containing food products and disposed between the shelves, a transparent jar adapted to contain a specimen of the goods contained in said sealed cans, a support for said jar adapted to rest upon the lower shelf and having approximately the same diameter as and the similitude of the sealed cans, a rotatable jar engaging member mounted upon said support and supporting the jar for rotation, and means for clamping the support between said shelves. 140
- 65 18. A merchandising and display equipment comprising the combination of a shelf adapted to support a supply of sealed opaque containers of goods, a transparent jar having a height approximating the height of a sealed container, and a diameter approximating the diameter of a sealed container and adapted to contain a specimen of the goods stored in said containers, and a cylindrical support for the jar having a height approximately the same as the height of the sealed containers and a diameter approximately the same as that of the sealed containers and having the similitude of said containers, a rotatable member mounted upon said support and supporting and engaging the jar, and manually operable means projecting through the side wall of the support whereby the jar may be rotated. 145
- 70 19. A merchandizing and display equipment comprising in combination a shelf adapted to support two tiers or sealed opaque cylindrical containers, a transparent jar having a diameter approximately the same as the diameter of one of the sealed containers and adapted to contain specimens of the goods in said containers, a support for the transparent jar having approximately the same diameter and height as one of the sealed containers and adapted to be disposed in the lower tier with said containers, and a rotatable jar holder mounted upon the upper end of said support. 150

said support detachably engaging the upper and lower shelves and holding the support from bodily movement.

17. A display device adapted to be used in connection with closed cans and for displaying a transparent sample jar of the goods in said cans including a rotatable jar holder, a support for the holder, the jar holder being mounted on the support for rotation around a vertical axis, a base for the support and a vertically extensible member carried by said base and adapted to engage an upper shelf to thereby force the base down against a lower shelf and clamp the support between the two shelves and hold the support against bodily movement.

18. A merchandising display equipment including in combination two shelves adapted to sup-

port between them sealed opaque cylindrical containers, a support adapted to rest upon the lower shelf, a rotatable jar holder mounted upon said support and having an upwardly extending peripheral guard, a transparent jar seated upon said support and within the peripheral guard and having a height such that the distance between the top of the jar and the under face of the upper shelf is less than the height of said peripheral flange whereby the jar cannot be removed from the holder without removing the support from the shelf, and means carried by the support and removably holding the support from detachment from the shelf.
